DESIGN FOR A BROOCH OR SIMILAR ARTICLE

John Rubel, New York, N. Y.

Application October 9, 1943, Serial No. 111,317

Term of patent 3½ years

To all whom it may concern:

Be it known that John Rubel, a citizen of the Republic of France, who has declared his intentions of becoming a citizen of the United States, residing in New York city, in the county of New York and State of New York, has invented a new, original, and ornamental Design for a Brooch or Similar Article, of which the following is a specification, reference being had to the accompanying drawing, forming part thereof.

Fig. 1 is a plan view of a brooch or similar article showing my new design, and

Fig. 2 is an elevational edge view thereof.

I claim:

The ornamental design of a brooch or similar article, substantially as shown.

JOHN RUBEL.
